(57) **CLAIM**

The ornamental design for an implantable monitor delivery device handle, as shown and described.

DESCRIPTION

FIG. 1 is a first side view of the implantable monitor delivery device handle showing my new design;

FIG. 2 is a front view of the implantable monitor delivery device handle;

FIG. 3 is a rear view of the implantable monitor delivery device handle;

FIG. 4 is a second side view of the implantable monitor delivery device handle;

FIG. 5 is a top view of the implantable monitor delivery device handle;

FIG. 6 is a bottom view of the implantable monitor delivery device handle; and,

FIG. 7 is an orthogonal view of the implantable monitor delivery device handle.

The broken line showing of the trigger assembly, grip, nozzle, and other surface features is included for the purpose of illustrating portions of the implantable monitor delivery device handle and forms no part of the claimed design.

1 Claim, 4 Drawing Sheets
